AUTOMATICALLY REVERSIBLE GEAR PUMP
Robert W. Erikson and Nils Einar Swedberg, Rockford,
Ill., assignors to Sundstrand Corporation, a corpora-
tion of Illinois

Filed Sept. 12, 1966, Ser. No. 589,150
7 Claims. (Cl. 103—126)

This application is a continuation-in-part of our co-pending application Ser. No. 455,217, filed May 12, 1965, now abandoned.

This invention relates generally to hydraulic pumps for delivering fluid under pressure and more particularly to a new and improved gear pump.

In compressor units a small pump is conventionally provided for supplying lubricating fluid to the various bearings in the compressor. These lubricating pumps are connected in some manner to be driven by the compressor drive shaft. This drive shaft is usually driven by a three phase electric motor. In the installation of such compressors the direction of rotation of the three phase motor and hence the compressor drive shaft, depends upon how the installing electrician connects the motor to the available source. It has been found difficult for the electrician to connect the motor so that the compressor drive shaft and the lubricating pump rotate in the same direction in all installations. For this reason automatically reversible lubricating pumps have been provided for pumping fluid out the same outlet passage regardless of the direction of rotation of the pump input shaft.

It is a primary object of the present invention to provide a new and improved gear type pump which maintains a unidirectional output flow regardless of the direction of rotation of input shaft.

Another object of the present invention is to provide a new and improved reversible gear type pump of the type having a rotating outer gear driven by an input shaft and an inner gear meshing with the outer gear and eccentrically mounted with respect to the outer gear so that the expanding gear teeth spaces receive inlet fluid and the contracting gear spaces compress and discharge fluid from the pump. An indexable port plate is provided adjacent the relatively rotating outer and inner gears. As the pump begins rotation in one direction torque is transmitted to the port plate, which carries the inner gear, so that the port plate indexes to a position where high pressure fluid flows through a port therein to a stationary outlet passage in a member adjacent the port plate. If the input shaft begins rotation in the opposite direction, torque is transmitted to the port plate, rotating it approximately 180 degrees from the position noted above so that high pressure fluid flows to the stationary outlet recess even though the drive shaft rotates in the opposite direction.

It is a further object of the present invention to provide a new and improved gear pump of the type described above in which the indexing torque is applied to the port plate partly by the engagement therewith by the rotating outer ring gear, and partly by a drive sleeve connected to the ring gear and frictionally engaging a portion of the periphery of the port plate. The cooperation of the frictional engagement of the outer gear and the cylindrical drive sleeve with the port plate assures the proper indexing of the plate. Stops are provided for limiting the indexing movement of the valve plate to approximately 180 degrees so that the ports therein and the pinion carried thereby reverse if the direction of rotation of the input shaft reverses.

A still further object of the present invention is to provide a new and improved gear pump of the type described above in which the inlet and outlet ports are axially disposed. In this manner the pump may be constructed so

2

that it fits on the compressor shaft as a unit with all parts aligned with respect to the input shaft. This has a decided advantage over radial porting gear pumps in that it is unnecessary to accurately align the port plate with respect to the surrounding housing member which in a radial pump would conventionally include the stationary inlet and outlet ports.

Another object of the present invention is to provide a new and improved gear pump of the type described in which the outer ring gear is separate from the input shaft so that the pumping elements may be connected to the input shaft as a unit. The cylindrical drive sleeve mentioned above, which is connected to the ring gear, projects axially therefrom so that it may be fitted over one end of the drive shaft and fixed thereto and in this manner the input shaft drives the outer ring gear through the sleeve. This provides a unitary and simplified gear pump which may be fitted over and aligned with respect to the drive shaft without concern for the accurate alignment of the pumping elements with respect to other portions of the device.

A further object of the present invention is to provide a new and improved gear pump of the type described above in which the input shaft is vertically disposed to increase the frictional force between the outer ring gear and the port plate to provide the necessary indexing force on the plate.

A still further object of the present invention is to provide a new and improved gear pump of the type described above particularly adapted for horizontal installations which includes a resilient spring means for biasing the port plate into engagement with the ring gear so that the ring gear exerts a sufficient frictional force on the port plate to assure proper indexing thereof.

Another object of the present invention is to provide a new and improved gear pump of the type described suitable for use with outer and inner gears of either the well known crescent type or the gear rotor type in which no crescent is utilized.

A further object of the present invention is to provide an improved gear pump of the type described above with novel means for relieving excessive fluid pressure.

Other and further objects of the present invention will be readily apparent from the following detailed description taken in connection with accompanying drawings, in which:

FIG. 1 is a longitudinal section of a gear pump embodying the present invention on a vertical compressor shaft within a reservoir in the compressor;

FIG. 2 is a cross-section, taken generally along line 2—2 of FIG. 1, showing eccentrically mounted gears and a crescent in the space between the gears;

FIG. 3 is a cross-section taken generally along line 3—3 of FIG. 1 illustrating one face of the port plate;

FIG. 4 is a cross-section taken generally along line 4—4 of FIG. 1 showing one face of the cover plate;

FIG. 5 is a fragmentary view taken generally along line 5—5 in FIG. 1 showing the other side of the port plate;

FIG. 6 is a longitudinal section of another form of the present invention particularly suited for use with horizontal compressor shafts;

FIG. 7 is an elevational view, partly in cross-section, of still another form of the invention with gear rotor type gears;

FIG. 8 is a longitudinal section of another form of the present invention;

FIG. 9 is a cross-section taken generally along line 9—9 in FIG. 8 showing one side of the cover plate; and

FIG. 10 is a cross-section taken generally along line 10—10 of FIG. 8 showing the gear assembly.

While illustrative embodiments of the present invention are shown and described in detail herein it should be understood that the present invention is susceptible of embodiment in many different forms and that the embodiments illustrated are to be considered an exemplification of the principles of the invention and are not intended to limit the invention thereto. The scope of the invention will be pointed out in the appended claims.

Referring to the drawings and particularly to FIG. 1, a vertically disposed shaft 10 is the main drive shaft for a compressor, the details of which form no part of the present invention and are therefore not shown. Suffice it to state that the shaft 10 may be driven by a suitable three phase electric motor. A reservoir is located within the compressor housing 11 and holds a suitable supply of lubricating fluid for the various bearings in the compressor.

The present hydraulic gear pump generally designated by the numeral 14 is mounted on the outboard end of the compressor shaft 10. Shaft 10 drives the pump 14 which draws fluid from within the reservoir 11 and pumps fluid through a central passage 15 in shaft 10 to the various bearing locations. A generally cylindrical housing member 17 has a mounting flange 18 thereon adapted to be fixed to a stationary portion of the compressor by suitable fastening means (not shown). A bore 20 is provided in the upper end of the housing 17 for a bearing 21 which surrounds the outboard end of the input shaft 10. The outboard end of the housing 17 has a bore 22 therein larger than and aligned with the bore 20.

A generally cylindrical cover plate or member 25 closes the housing 17, and defines stationary inlet and outlet ports for the gear pump, as shown in FIGS. 1 and 4. Suitable threaded fasteners 26 fix the cover plate 25 to the housing 17. As shown more clearly in FIG. 4 an inlet port 27 extends through the cover member 25 and is in constant communication with fluid in the reservoir 11. A generally T-shaped outlet recess 28 is formed in the inside surface 29 of the cover member 25. Recess 28 includes a central leg 30 symmetrical about the center of the cover member and a radially projecting leg 31. As will appear more clearly hereinafter fluid flows from the reservoir through inlet port 27 to the pump and from the pump through outlet recess 28 regardless of the direction of rotation of input shaft 10. A stop pin 33 is fixed within the cover member 25 and extends inwardly towards the shaft 10 a short distance as shown in FIGS. 1, 4 and 5.

A generally cylindrical indexable port plate 35 is provided for maintaining the high pressure outlet of the pump 14 in communication with outlet recess 28. As shown in solid lines in FIG. 3, two generally arcuate ports 37 and 38 are provided in the inwardly facing surface of the port plate 35. Ports 37 and 38 may be either outlet or inlet ports depending upon the direction of rotation of input shaft 10. Diametrically opposed passages 39 and 40 communicate with the ports 37 and 38, respectively, and extend through to the outward face of the port plate 35. Passages 39 and 40 are spaced from the center of the port plate 35 a distance to communicate with either inlet port 27 or the leg 31 of the outlet recess 28 in the cover member 25.

As shown more clearly in FIG. 5 the port plate 35 has an outwardly facing peripheral recess 42 extending approximately 180 degrees plus the width of the stop pin 33. The recess 42 slidably receives the stop pin 33 so that, as shown in FIG. 5, the pin 33 will prevent counterclockwise movement of the port plate 35 beyond the position shown. Upon clockwise rotation of the port plate 35, pin 33 will prevent rotation of the port plate beyond the position where the passages 39 and 40 are reversed as shown in broken lines in FIG. 3.

A hollow shaft 44 is fixed within and extends through the port plate 35 projecting therefrom to the outboard end of the input shaft 10. The interior of the hollow shaft 44 continuously communicates with the elongated leg 30

of the outlet recess 28 and the passage 15 in the drive shaft 10. Note that the axis of shaft 44 is spaced from the axis of the input shaft 10 so that depending upon the indexed position of the port plate 35, the interior of shaft 44 will be aligned with either the upper or the lower end of the recess leg 30 in the cover member 25.

An outer ring gear 46 is provided with inwardly directed spaced teeth 47. Gear 46 is symmetrical about the axis of rotation of input shaft 10 and is driven thereby by a cylindrical drive sleeve 49 surrounding and engaging the outboard end of the input shaft 10, the periphery of the outer ring gear 46, and a portion of the indexable port plate 35. Sleeve 49 is pinned to the input shaft 10 and fixed by suitable means to the ring gear 46 so that the outer gear is driven continuously by shaft 10. Sleeve 49 slidably engages the periphery of the port plate 35 to support the same and to assist in indexing the port plate. Ring gear 46 has a radial surface 51 which frictionally engages the inward face of the port plate 35 to also assist in indexing the port plate. It should be understood that the indexing of the port plate 35 occurs only during pump starting and that during normal running operation the port plate 35 remains stationary and the ring gear 46 and the drive sleeve 49 rotate with respect to the port plate 35.

The bore 22 in the housing is spaced from the sleeve 49 so that it does not retard rotation of the sleeve or the indexing of the port plate 35.

An internal pinion or gear 53 is rotatably mounted on the hollow shaft 44 and has outwardly extending teeth 54 meshing with the teeth 47 on the outer gear 46 as shown in FIGS. 1 and 2. As the pinion or roller gear 53 is mounted on shaft 44 it indexes with the port plate.

In operation, as the outer gear rotates it drives the inner gear about the axis of hollow shaft 44 so that low pressure fluid is drawn into the expanding spaces between the teeth and fluid in the contracting spaces is compressed and discharged. A crescent 56, fixed to the port plate 35 by suitable threaded fasteners, projects from the port plate into the space between the teeth on gears 46 and 53. Crescent 56 performs the conventional function in this type of pump of sealing the low pressure area or spaces from the high pressure area. As shown in FIG. 2 and assuming that ring gear 46 is rotating in a clockwise direction, low pressure fluid will be drawn in from port 37 in the valve plate and carried by the spaces between the gears which in association with the crescent 56 define chambers, to the contracting area of the gears adjacent the port 38 where the fluid is compressed and discharged through the port. If an excessive fluid pressure is developed in the contracting fluid chambers between the gears 46 and 53, the hydraulic force acting between the port plate 35 and cover member 25 will lift the port plate slightly (the play in shaft 10 permits the upward movement) from sealing engagement with the cover plate 25 permitting fluid to escape into the low pressure bore 22, thus relieving the excessive pressure. Fluid leakage may also occur due to separation between the gears and the port plate or the gears and the input shaft, and in these instances the high and low pressure chambers between the gears are short circuited.

One of the advantages of the present device is that the pump 14 may be mounted on the outboard end of the compressor shaft 10 without maintaining an accurate alignment between the port plate 35 or the gears with the stationary cover member 25 which defines the stationary outlet port. More particularly, the indexable port plate 35 and the gears 46 and 53 may be fitted as an aligned unit on the end of the compressor shaft simply by fitting the drive sleeve 49 over the shaft and fixing it thereto. This serves to align not only the ring gear 46 with respect to the shaft, but also the port plate 35 so that during indexing thereof it rotates about the axis of shaft 10. Small misalignments between the port plate 35

and the inlet and outlet ports in the cover member 25 do not adversely affect the operation of the pump.

While the operation of the present device as shown in FIGS. 1 to 5 is believed clear from the description above, it may be helpful to review the automatic reversal on clockwise and counterclockwise rotation of the input shaft 10. Assume first that the input shaft 10 begins rotation in a clockwise direction as viewed in FIG. 3. The vertically disposed shaft 10 through the sleeve 49 begins rotating the outer ring gear 46. At the same time the frictional engagement of sleeve 49 with the periphery of the port plate 35 and the frictional engagement of radial surface 51 of ring gear 46 with the radial surface of port plate 35 serve to index the port plate in a clockwise direction until the end of recess 42 engages the pin 33, which serves to stop the port plate in the position shown in FIGS. 1, 3 and 5. It should be noted that the weight of the vertical shaft 10 on the ring gear 46 provides frictional force between the face 51 and the valve plate to aid proper indexing and to prevent axial separation between the port plate and the cover, the port plate and the gears, and the gears and the input shaft, in the embodiment shown in FIGS. 1 to 5. In this position, port 37 and passage 39 communicate with inlet port 27 and the diverging or expanding spaces between the gears 46 and 53. High pressure fluid from the converging spaces, which are approximately diametrically opposed to the diverging spaces as shown in FIG. 2, pass through port 38, outlet passage 40 and into the outlet recess 28. High pressure fluid in the outlet recess 28 flows through the hollow shaft 44 and into the axial passage 15 in the compressor shaft 10 to the various bearing locations for lubrication thereof.

On the other hand assume that during installation the motor driving the compressor shaft 10 is connected to rotate the shaft in a counterclockwise direction as viewed in FIG. 3. Also assume that the various pump parts are initially in the positions shown in FIGS. 1 to 5 at rest. Shaft 10 through the drive sleeve 49 begins rotating the outer gear 46 about the axis of shaft 10. At the same time the outer gear 46 and the sleeve 49 frictionally engage the valve plate 35 and rotate it in a counterclockwise direction until the stop 33 abuts the opposite end of the recess 42, thereby stopping the valve plate 35. The valve plate then assumes the position shown in dotted lines in FIG. 3. Note that during this indexing movement of the valve plate that the pinion shaft 44 and the crescent 56 also index 180 degrees, as they are fixed to the port plate 35. Fluid then enters the pump through inlet port 27 in the cover plate 25 but now flows to the expanding gear spaces through port 38 in the valve plate which is then aligned with the inlet port 27. High pressure fluid flowing from the gears passes through port 37 in the valve plate and into the recess 28, the leg portion 31 of which is then aligned with passage 39. High pressure fluid in recess 28 flows through the hollow shaft 44 and passage 15 in shaft 10 in the same manner as in the clockwise operation described above.

In this manner the present device maintains a unidirectional output through a stationary outlet passage by effectively indexing the gears and port plate so that the high pressure and low pressure ports in the valve plate always communicate respectively with the outlet and the inlet ports in a stationary port member regardless of the direction of rotation of the pump input shaft.

In some installations it is desirable to provide a gear pump of the type described adapted to be driven by a horizontally oriented compressor drive shaft. Such a pump is shown in FIG. 6 incorporating the principles of the present invention. The parts in FIG. 6 which are the same as the parts in FIGS. 1 to 5 are designated with like reference numerals. A pump housing 18' is provided similar in construction to the housing 17 except that it has an axial extension 60 with a counterbore 22' therein. A radial inlet passage 62 extends through the housing

18' and is adapted to carry low pressure fluid to the pump 14'. In place of the stationary cover member 25 in the FIGS. 1 to 5 embodiment, a non-rotatable, axially slideable valve member is provided in bore 22'. A stop pin 33', fixed within the valve member 25', slides within the recess 42 in the indexable valve plate 35 in the same manner as in the pump 14. The stop pin 33' performs the additional function of preventing rotation of the valve member 25' without retarding its axial movement. For this purpose pin 33' slides within an axial groove 61 in the bottom of bore 22'.

The cover plate 63 encloses the pump and is fixed to the open end of housing member 18' by suitable threaded fasteners 65. A tapered compression spring 66 engages the inside surface of the cover 63 and is seated at its other end in a central recess in valve member 25'. In this manner the valve member 25' is continuously urged into engagement with the face of the indexable port plate 35. If the pump 14' develops an excessive fluid pressure, the force of hydraulic fluid acting against valve member 25' will move it slightly axially against the force of compression spring 66 permitting fluid leakage between the valve member and the face of the port plate 35, thus relieving the excessive pressure. Fluid leakage may also occur due to separation between the port plate and the gears or between the gears and the input shaft, and in these instances the high and low pressure chambers are short circuited.

The operation of the FIG. 6 embodiment is the same as that of the FIGS. 1 to 5 embodiment, except that the frictional indexing force of gear face 51 on the indexible port plate 35 and the sealing engagement between the parts is produced as a result of the biasing effect of spring 66. In this manner the present device is usable as well in horizontal installations.

In some installations it may be desirable to eliminate the inner gear support shaft 44 in both the FIGS. 1 and 6 embodiments, particularly when the pump application requires low discharge pressures. In such a case, the inner gear 53 would be supported and float between the outer gear 46 and the crescent 56. Discharge fluid from the pump would flow through a central bore in the inner gear and a complementary bore in the port plate 35, rather than through hollow shaft 44.

It should be understood that the principles of the present invention are applicable not only to crescent-type gear pumps such as shown in FIGS. 1 to 6, but also to gear rotor pumps of the type in which the inner and outer gear teeth are in sliding contact over the non-meshing arc of the gears. The outer and inner gear elements 70 and 71 respectively of such a gear rotor are shown in FIG. 7. In a gear rotor as opposed to a crescent pump, the gear teeth are elongated and shaped so that the engagement between the outer and inner gear teeth provide the necessary sealing between the low and high pressure sides of the pump. No crescent is necessary in this type of pump. When used in the present pumping device, the outer gear member 70 would be driven by the cylindrical drive sleeve 49 in the same manner as outer ring gear 46. The inner gear 71 would be rotatably mounted on pinion shaft 44 in the same manner as inner gear 53. The operation of the gear rotor pump would be substantially the same as that described above.

The hydraulic unit shown in FIGS. 8 to 10 is generally similar in construction and operation to those described above except for the provision of a separate resiliently biased sealing plate between the gears and the compressor shaft.

The pump 114 is seen to include a housing member 118 forming part of the housing of an associated compressor having a sleeve bearing 121 supporting the outboard end of compressor shaft 110. Shaft 110 has a suitable center bore 115 which serves as the outlet passage for the pump in either direction of rotation. The housing member 118 has a central recess 122 for receiving the

pumping elements and an inlet passage 162 communicating with the recess. A cover member 125 is fixed to the recessed end of the housing 118 and has formed therein a chamber 127 communicating with recess 122 and inlet passage 162. Chamber 127 extends radially and communicates with an arcuate inlet port 127A also formed in the cover 125. Opposite the port 127A (which is a low pressure port) is an arcuate port 128 which is a high pressure port in the cover 125. Port 128 continuously communicates with a radial passage or recess 131 which communicates continuously with the outlet passage 115 in the shaft 110.

Fixed to the end of shaft 110 are pumping elements similar to that shown in the FIG. 7 embodiment including sleeve 149, outer gear 70, inner gear 71, port plate 135 and hollow shaft 144. Pin 133 is mounted in cover plate 125 and limits indexing movement of the port plate 135 in a manner similar to that described above with the other embodiments.

In the FIGS. 8 to 10 embodiment, the outer gear is somewhat larger than the outer diameter of shaft 110 so that a suitable annular adapter 149A is provided fixed to shaft 110 and sleeve 149 by radially extending key pins 150.

This embodiment is also somewhat different from the others in that the gear elements are spaced from the end of compressor shaft 110 and a sealing plate 160 is located therebetween with one face thereof sealingly engaging the gears 70 and 71. Shaft 110 has a counterbore 162 in the end thereof receiving a coiled compression spring 163 which biases a hollow piston 164 against the sealing plate 160, thus urging the plate against the gears and maintaining sealing engagement between the parts. If an excessive fluid pressure develops in the outlet of the pump, i.e. passage 131 and hollow shaft 144, fluid pressure acting against piston 164 and plate 160 will urge the sealing plate away from the gears against the force of spring 163 permitting fluid to leak between the plate and the gears and into the low pressure recess 122 through slot 166 in shaft 110 and also between high and low pressure fluid chambers.

The operation of the embodiment of FIGS. 8 to 10 is substantially the same as that described above with reference to FIGS. 1 to 7.

It should be understood that the present invention is not limited to use with a compressor and finds applicability in many types of rotating machinery.

We claim:

1. In a gear pump, the combination comprising: an input shaft rotatable about an axis, an outer ring gear adjacent one end of said input shaft and driven thereby, an indexible port plate slidably engaging said outer ring gear and having two generally arcuate ports extending axially therethrough, said port plate having an arcuate recess in the periphery thereof extending substantially 180 degrees, a hollow shaft mounted in said port plate and extending within said ring gear, said hollow shaft having an axis spaced from said input shaft axis, an inner pinion gear mounted for rotation on said hollow shaft and meshing with said outer ring gear, a passage in said input shaft communicating with the interior of said hollow shaft adapted to convey fluid from the pump, a relatively stationary cover member engaging one side of said port plate, a projection on said cover member extending into said port plate recess for limiting the indexing movement thereof whereby when the input shaft rotates the port plate, the hollow shaft and inner gear rotate approximately 180 degrees to reverse the location of the arcuate ports, an outlet recess in said cover member in continuous communication with the interior of said hollow shaft, said outlet recess extending radially in said cover member to selectively communicate with said arcuate ports in said port plate, an inlet passage in said cover member located to selectively communicate with the arcuate ports in said port plate, whereby inlet fluid enters through said inlet

passage and passes through one of said arcuate ports, and high pressure outlet fluid passes through one of said arcuate ports, into said outlet recess, through said hollow shaft and out said input shaft passage regardless of the direction of rotation of said input shaft.

5 2. A combination as defined in claim 1, wherein said outer ring gear is separate from said input shaft and has an outer diameter substantially equal to the input shaft diameter, a cylindrical sleeve surrounding a portion of said input shaft and said outer ring gear, said sleeve being fixed to said input shaft and said gear to transfer torque therebetween, said sleeve extending around a portion of said port plate and supporting said plate for rotation about the axis of said input shaft, said sleeve slidably and frictionally engaging said port plate so that the sleeve indexes said port plate, a housing surrounding said gears and port plate, said cover member being fixed to said housing member, the inner surface of said housing being spaced from said sleeve and port plate so that the port plate may be readily indexed.

10 3. In a gear pump, the combination comprising: an input shaft adapted to be rotated about an axis, an outer gear driven by said input shaft, an inner gear meshing with said outer gear and rotatable about an axis spaced from said input shaft axis, an indexible port plate adjacent said gears having ports therein adapted to convey fluid to and from said gears, said inner gear axis being fixed with respect to said port plate, a relatively stationary port member having inlet and outlet ports therein adapted to selectively communicate with said indexible ports to maintain a unidirectional pump output irrespective of the direction of rotation of said input shaft, means separate from said stationary port member for supporting said port plate for rotation about the input shaft axis to assure the proper alignment therebetween, said outer ring gear being separate from said input shaft, and means for connecting and aligning said outer ring to said shaft whereby the port plate, the inner gear, and the outer gear may be connected as a unit and aligned with respect to the input shaft.

15 4. A combination as defined in claim 3, and further including means for relieving excessive pressure in said outlet port.

20 5. A combination as defined in claim 4 wherein said means for relieving excessive pressure in said outlet port includes a resiliently biased sealing plate between the end of said input shaft and said gears.

25 6. In a gear pump the combination comprising: an outer gear member, sleeve means surrounding and fixed to said outer gear member and extending axially therefrom, means for rotatably fixing said sleeve means around an input shaft so that the gear pump is aligned therewith, an indexible plate adjacent said outer gear, said sleeve means extending axially from said outer gear around said indexible plate for radially supporting the same, said sleeve frictionally engaging said plate, an inner gear meshing with said outer gear and mounted for rotation about an axis spaced from the axis of said outer gear, means for maintaining the axis for rotation of said inner gear stationary with respect to said indexible plate, said inner and outer gears defining upon relative rotation therebetween expanding and contracting fluid chambers, inlet port means for conveying fluid to the expanding fluid chambers, outlet port means for conveying fluid from the contracting fluid chambers, and means for limiting the indexing movement 30 of said indexible plate so that the contracting fluid chambers communicate with said output port means regardless of the direction of rotation of said outer gear member.

35 7. In a gear pump, the combination comprising: an input shaft adapted to be rotated about an axis, an outer gear driven by said input shaft, an inner gear meshing with said outer gear and rotatable about an axis spaced from said input shaft axis, an indexible port plate adjacent said gears having ports therein adapted to convey fluid to and from said gears, said inner gear axis being fixed with

respect to said port plate, a relatively stationary port member having inlet and outlet ports therein adapted to selectively communicate with said indexible ports to maintain a unidirectional pump output irrespective of the direction of rotation of said input shaft, means separate from said stationary port member for supporting said port plate for rotation about the input shaft axis to assure the proper alignment therebetween, said means for supporting said port plate and said means for connecting the outer gear to the input shaft including a cylindrical sleeve surrounding a portion of said input shaft and fixed with respect thereto, said sleeve extending around said outer gear and fixed with respect thereto, and said sleeve further extending around a portion of said port plate and frictionally engaging the periphery thereof.
